A. H. NOBLE

LIP STICK HOLDER

Filed Nov. 4, 1926

Patented June 14, 1927.

1,632,765

UNITED STATES PATENT OFFICE.

ARTHUR H. NOBLE, OF PAWTUCKET, RHODE ISLAND, ASSIGNOR TO THEODORE W. FOSTER & BROTHER COMPANY, OF PROVIDENCE, RHODE ISLAND.

LIP-STICK HOLDER.

Application filed November 4, 1926. Serial No. 146,168.

This invention relates to certain new and useful improvements in lip stick holders, and the primary object thereof is to provide a holder having improved means which enable 5 a worn lip stick to be easily and quickly removed and a fresh one applied from the bottom of the holder.

A further object of the invention is to provide a holder which has novel means of 10 simple, compact and economical construction for effecting easy, quick and positive movement of the lip stick into and out of the holder.

The invention has still further and other 15 objects which will be later set forth and manifested in the course of the following description.

In the drawings:—

Fig. 1 is a side elevation of the invention 20 with the parts in inoperative and housed position;

Fig. 2 is a longitudinal sectional view showing the parts in operative position;

Fig. 3 is a section on line 3—3 of Fig. 2.

25 In proceeding in accordance with the present invention a sleeve-like casing 1 is employed having a bead 2 near its top that forms a stop for a cap 3. A rotatable circular head 4 engages the base of the casing 1 and is mounted on an inner rotary sleeve 5, the latter being surrounded by an outer fixed 30 sleeve 6. The upper end of the casing 1 is inturned as indicated at 7, so as to hold the sleeve 6 against longitudinal movement.

35 The sleeve 6 is formed with a spiral slot 8, while the sleeve 5 is formed with an axial slot 9. The lip stick 10 is formed with a metallic ferrule 11, the latter having an outwardly projecting pin 12 thereon. The cap 4 is removable from the inner tube 5, and is provided with an instruck part 14 which latter enters a slot 9' of an offset 15 of sleeve 5 when the parts are in operative position.

40 As shown in Fig. 2, the lower end of the sleeve 5 where offset at 15, receives the head 4 and also provides a shoulder 16 on which the lower end of the outer sleeve 6 seats. A slot 10' is formed in the inturned edge of the casing.

45 50 In operation the cap 4 is removed and the

lip stick inserted into the bottom end of the casing so as to have its pin 11 enter the spiral slot 8 and the slot 9, whereupon the cap 4 is applied to the end 15 of the sleeve 5 and serves as a means of rotating the latter there- 55 by effecting in and out movements of the lip stick with respect to the casing 1.

From the foregoing it will be seen that the lip stick is thus inserted from the bottom of the casing, and that a worn lip stick 60 can be easily and quickly removed and a fresh one applied. The slot 10' enables the pin 12 to pass therethrough so as to expel or eject the lip stick upon same being used up. 65

Having thus described my invention what I claim as new and desire to secure by Letters Patent is:

1. In a lip stick holder, a casing having an inturned top edge, a fixed sleeve in the casing having a spiral slot extending through its bottom end, a rotary sleeve in the fixed sleeve having an axial slot extending through its bottom end, said rotary sleeve having its lower end offset outwardly and slotted, a lip 70 stick having a ferrule thereon, a projection on the ferrule, receivable in the sleeve slots, the lip stick being insertable into the rotary sleeve from the bottom thereof, and a head on the offset part of the rotary sleeve having an instruck part received in the slot of the offset part. 75

2. In a lip stick holder, a casing, a fixed sleeve in the casing having a spiral slot extending through its bottom end, a rotary 85 sleeve in the fixed sleeve having an axial slot extending through its bottom end, a lip stick having a ferrule thereon provided with a projection that is received in the sleeve slots, the lip stick being insertable in the casing 90 through the bottom end of the rotary sleeve, and a head for rotating the rotary sleeve removably connected thereto.

3. In a lip stick holder, a casing having a lip stick inlet in its bottom and an outlet at 95 its top, a lip stick having a ferrule thereon, rotary means in the casing to actuate the lip stick into and out of the outlet, means communicating with the inlet whereby to connect the ferrule to said rotary means upon 100

insertion of the lip stick into the inlet, and means to actuate the rotary means.

4. In a lip stick holder, a casing having a lip stick inlet in its bottom and an outlet at its top, a lip stick having a ferrule thereon, rotary means in the casing to actuate the lip stick into and out of the outlet, means communicating with the inlet whereby to connect the ferrule to said rotary means

upon insertion of the lip stick into the inlet, and also communication with the outlet whereby to eject the ferrule through the outlet when said connecting means aligns with the outlet.

In testimony whereof I have signed my name to this specification.

ARTHUR H. NOBLE.
